UNITED STATES PATENT OFFICE

2,267,635

SAVINGS BANK

Jerome B. Aronsen, Chicago, Ill., assignor to
 Banthrico, Inc., Chicago, Ill., a corporation of
 Illinois

Application March 20, 1941, Serial No. 384,266

3 Claims. (Cl. 220—55)

The present invention relates to banks and particularly to toy banks wherein a metal base plate is associated with a body portion made of plastic material. The invention however may be applied to numerous devices wherein a metal plate is attached to a plastic housing.

The object of the present invention is to provide means whereby the metal base plate of the bank removably is associated with a thin plastic coin bank housing in such fashion as to provide adequate support for the base plate and to strengthen the housing and prevent its warping or cracking. The metal base plate is provided with a coin slot and a spring guard therefor. A lock on one end and a lug on the opposite end of the base plate cooperate with metal flanges associated with the housing to permit ready removal of the base plate.

Other objects and advantages of the present invention will appear more fully as the description proceeds, reference being had to the accompanying drawing wherein a preferred embodiment of the invention is shown. It is to be understood however that the drawing and description are illustrative only and that the invention is to be limited only insofar as it is limited by the claims.

In the drawing,

Fig. 1 is a view of a side elevation of a toy bank embodying the present invention, a portion of the side being cut away to show the junction between the housing and the base plate;

Fig. 2 is a view on the line 2—2 of Fig. 1;

Fig. 3 is a plan view of the bottom of the bank; and,

Fig. 4 is a perspective view of the metal stamping which is associated with the housing and which removably receives the metal base plate.

Referring now to the drawing, the toy bank embodying the present invention includes a housing 10. The housing 10, which for purposes of this illustration simulates a small house, is made of any suitable plastic material and in this case has a rectangular base. The lower portions 11 of the housing are offset and spaced from the main sides by shoulders 12, thereby providing a rectangular base slightly larger than the rectangular section of the housing proper.

An intermediate metal portion 15 (best shown in Fig. 4) is provided between the base of the housing and a metal base plate. This intermediate portion 15 is a rectangular metal stamping which includes vertical peripheral flanges 16 adapted to bear within and against the enlarged base portions 11 of the housing. Projecting in-

wardly from and at the top of the flanges 16 are shoulders 17 on which rest the inner surfaces of the shoulders 12 of the housing. The free ends of shoulders 17 are turned downwardly and inwardly as shown by flanges 18, the lower part of which terminate in a horizontal plane somewhat above the lower end of flanges 16. This intermediate portion 15 is secured to the base portion 11 of the housing and against the offset shoulders 12. In order to strengthen the side wall 11 and provide adequate connection of the stamping 15 to the plastic housing, I use two strips 20 running longitudinally of the housing and connect them by rivets 19 to the flanges 16.

15 A metal base plate 25 is adapted loosely to fit within the depending flanges 16 and to bear against the lower inturned flanges 18 of the intermediate metal portion 15, thereby closing the open bottom of the plastic housing 10. A coin slot 26 and a spring slot guard mechanism 27 are provided on the base plate.

20 25 A lug 28 integral with the base plate and spaced from one end thereof is stamped from the base plate. The lug 28 is inclined to the plate and is adapted to clamp a lower inturned flange 18 of the intermediate portion 15 between it and the base plate, thereby holding the base plate in position.

25 30 A lock mechanism 30 is mounted on the inner face of the base plate near the end thereof opposite the lug 28. Retractable lugs 31, actuated by the lock mechanism, extend toward the end of the plate. In their extended position, the lugs 31 overlie a lower inturned flange 18 and 35 hold the base plate securely against the bottom surfaces of the flanges 18. When retracted, the lugs 31 clear the flange 18 and the base plate readily may be removed.

35 40 From the above description, it is apparent that I have provided a simple and effective means for removably mounting a metal base plate to a housing of plastic material.

Having thus described my invention, what I claim as new and desire to secure by Letters 45 Patent is:

1. A toy bank comprising a housing of plastic material, the bottom of said housing being open, a metal stamping having flanges which abut the inner sides of the housing and are secured thereto adjacent the bottom thereof, said stamping also having flanges extending inwardly and downwardly from said first named flanges, the free ends of said latter flanges terminating in horizontal extensions, a base plate enclosing said bottom opening and having means for removable

engagement with said horizontal extensions, said means including extension overlying lugs spaced from opposite ends of said base plate, one set of lugs being retractable to permit removal of said base plate.

2. A toy bank comprising a housing of plastic material having an open bottom, the sides of said housing having the lower portions thereof offset outwardly by means of shoulders, a metal stamping including flanges which abut the offset portions interiorly thereof and are secured thereto by means of rivets, webs which abut the shoulders of said housing, and flanges extending inwardly and downwardly from said webs, the free ends of said latter flanges terminating in substantially horizontal extensions, a base plate enclosing said bottom opening and having a lug stamped from one end thereof and adapted to

overlie a horizontal extension, retractable extension overlying lugs at the opposite end of said base plate, and a lock mechanism adapted to actuate said latter lugs to remove said base plate.

3. A toy bank comprising a housing of plastic material having an open bottom, a metal stamping secured to the inner sides of said housing adjacent the open end thereof, said stamping having inwardly and downwardly extending flanges terminating in substantially a horizontal plane, a metal base plate enclosing said bottom opening and engaging said flanges, lugs on opposite ends of said base plate overlying said flanges to hold said base plate in position, the lugs at one end of said plate being retractable to permit removal of said base plate.

JEROME B. ARONSON.
